DESIGN FOR A COMBINED MAKE-UP BOX AND MIRROR

Max J. Pinski, New Orleans, La.

Application December 7, 1938, Serial No. 81,614

Term of patent 3½ years

To all whom it may concern:

Be it known that I, Max J. Pinski, a citizen of the United States, residing at New Orleans, in the parish of Orleans and State of Louisiana, have invented a new, original, and ornamental Design for a Combined Make-up Box and Mirror, of which the following is a specification, reference being had to the accompanying drawing forming a part thereof.

In the drawing:

Fig. 1 is a front view of a combined make up box and mirror, showing my new design;

Fig. 2 is a plan view thereof; and

Fig. 3 is a side view thereof.

I claim:

The ornamental design for a combined make-up box and mirror, as shown.

MAX J. PINSKI.
